UNITED STATES PATENT OFFICE.

LOUIS GREENBERG AND GUSTAF OLSON, OF CHICAGO, ILLINOIS, ASSIGNEES OF ONE-
THIRD TO WILLARD M. McEWEN, OF CHICAGO, ILLINOIS.

AIR-CIRCULATING DEVICE.

1,125,685.

Specification of Letters Patent. Patented Jan. 19, 1915.

Application filed September 19, 1913. Serial No. 790,632.

To all whom it may concern:

Be it known that we, LOUIS GREENBERG and GUSTAF OLSON, citizens of the United States of America, and residents of Chicago, county of Cook, and State of Illinois, have invented certain new and useful Improvements in Air-Circulating Devices, of which the following is a specification.

The main objects of this invention are to provide an improved form of electric fan adapted to have an oscillatory movement during the operation thereof; to provide improved mechanism for causing said oscillatory movement, and to provide an improved arrangement of said mechanism on said fan.

An illustrative embodiment of this invention is shown in the accompanying drawings in which—

Figure 1 is a side elevation of a fan, showing the mechanism by means of which it is oscillated, a portion of the lower part of the casing being omitted for the purpose of disclosing the said mechanism. Fig. 2 is an enlarged fragmentary sectional detail taken on the line A—A of Fig. 1. Fig. 3 is a sectional plan view taken on the line B—B of Fig. 2. Fig. 4 is a fragmentary sectional detail taken on the line C—C of Fig. 3. Fig. 5 is a rear elevation of the worms and gears connecting the driving mechanism with the motor. Fig. 6 is a detail in perspective of one of the shiftable clutch members.

In the construction shown in the drawings the device comprises a supporting member or base 1, a motor 2 mounted in a casing 3 and connected to rotate a fan 4. The motor 2 together with its casing 3 and fan 4, which is hereinafter referred to as the blower mechanism, is supported on the member or base 1 by means of a shaft 5 rigidly secured to the casing 3 and journaled in the member 5 so that the blower mechanism is adapted to be given a relative rotary movement with respect to said supporting member.

The mechanism for oscillating the blower mechanism is concentrically arranged about the shaft 5 on the under side of the motor casing 3. A transversely disposed annular flange or track 6 is supported at the upper end of the base 1 and has apertures 7 formed therein so as to constitute a rack with which the pinions or star wheels 8 are adapted to mesh. The pinions 8 are rotatably mounted

on a shaft 9 inwardly of the anti-friction rollers 10 which are also loosely journaled thereon in position to bear on respectively opposite sides of the flange 6 outwardly of the apertures 7.

The shaft 9 is journaled in a bearing 11 depending from the motor casing 3, and in the vertical shaft 5, which supports the blower mechanism on the supporting member 1. It is positively driven by the motor 2 through the medium of the worms 12 and 13 and the gears 14 and 15. The worm 12 is carried on the shaft 16 of the motor 2 and meshes with the gear 14 carried on a vertically disposed shaft 17 journaled in a bearing 18 integrally formed on the motor casing 3. The worm 13 is carried on the shaft 17 and meshes with the gear 15 secured to the shaft 9.

Clutch mechanisms are provided for alternately connecting the pinions 8 with the shaft 9 which include sleeves 19 slidably mounted on the shaft 9 and splined thereto by means of keys or shoulders 20, Fig. 6. The sleeves 19 are provided with shoulders 21 or serrations 22 which are adapted to coact with other shoulders or serrations 23 formed on collars 23 carried by the pinions 8 for locking the clutches to the respective pinions. The sleeves are connected together by a rod 24 and forks 25 so as to be simultaneously shifted to connect one of the pinions with the shaft 9 and disconnect the other.

The rod 24 is shiftably mounted above the shaft 9 and the depending arms or forks 25 are rigidly secured thereto and partially embrace the respective sleeves 19. The clutch mechanisms are shifted through the engagement of shoulders 26 carried on the sleeves 19, with the cam or arm 27 attached to the member 1 and extending upwardly above the plane of the flange 6 inwardly thereof. The shoulders or lugs 26 are integrally formed on the sleeves 19 and spaced apart angularly about 90 degrees. The faces of the lugs 26 which come into contact with the arm 27 are inclined so as to facilitate the shifting of the sleeves 19. The arm 27 is bent outwardly so as to form an inclined surface opposing the inclined surfaces on said lugs 26. The arm 27 is preferably made of resilient material so that it will yield slightly as the lugs 26 engage the same. The rod 24 is yieldingly retained in one or the other of the positions into which it

is shifted by means of a pointed rod or detent 30 slidably mounted at one side of the rod 24 and normally urged by the spring 31 to engage one or the other of the notches 32 formed in said rod.

The gear 14 is loosely mounted on the shaft 17 and has a collar 33 rigidly secured thereto and provided with a notch 34 adapted to receive the shoulder 35 on the latch 36 pivoted at 37 to the upper end of the shaft 17. When the shoulder 35 is in engagement with the notch 34, the shaft 17 will be caused to rotate and operate the driving mechanism for oscillating the fan. When the latch 36 is in the position shown in Fig. 1 the driving mechanism will remain inoperative and the blower mechanism may therefore be operated without being oscillated.

The driving and clutch mechanisms are all housed within an apron 38 attached to the motor casing and depending therefrom so that said mechanisms are protected from injury. The worms and gears connecting the shaft 9 with the motor 2 are also protected by suitable housings as shown in drawings. A rheostat (not shown) is secured in the base 1 in the usual manner which is connected with a source of electricity by means of the conductor 39 and connected by other suitable conductors (not shown) with the motor 2. The rheostat is controlled by a switch arm 40 protruding through the slot 41 formed in the base.

The operation of the device shown is as follows: When it is desired to have the fan oscillate, the latch 36 is shifted so as to cause the shoulder 35 to enter the notch 34. The current is turned on by means of the switch arm 40 whereby the motor will rotate the fan 4 and at the same time revolve the shaft 9 through the medium of the worms 12 and 13 and the gears 14 and 15. Assuming that the shaft 9 is driven in the direction of the arrow 42, Fig. 5, and that the clutches are in the positions shown in Fig. 1, the blower mechanism will have a rotary movement with respect to the base in the direction of the arrow 43 shown in Fig. 3. When the blower mechanism has revolved so that one of the lugs 26 on one of the sleeves 19 engages the arm 27, the rod 24 will be shifted to the left of Fig. 3, thereby causing the disengagement of the one clutch and the engagement of the other. This shifting of the clutches will release the forward pinion 8 from engagement with the shaft 9 and cause the engagement of the rear pinion 8 with said shaft, whereupon the said rear pinion 8 operating on the rack 6 will cause the blower mechanism to rotate with respect to the base in the opposite direction. When one of the lugs 26 on the other sleeve 19 engages the arm 27 at the end of said reverse rotary movement of the blower mechanism, the rod 24 will be shift-

ed to the right of Fig. 3 whereupon the cycle of operations is repeated.

Although but one specific embodiment of this invention has been herein shown and described, it will be understood that numerous details of the construction shown may be altered or omitted without departing from the spirit of this invention as defined by the following claims.

We claim:

1. An air circulating device comprising blower mechanism, a member rotatably supporting said blower mechanism, an annular track carried by said member, driving mechanisms carried by said blower mechanism and engaging said track at opposite sides thereof, clutch mechanisms adapted to be shifted for alternately connecting said driving mechanisms so as to be operated by said blower mechanism for causing the relative rotation thereof on said supporting member, and means adapted to be actuated by said relative rotation for shifting said clutch mechanisms for oscillating said blower mechanism. 75 80 85 90

2. An air circulating device comprising blower mechanism, a member rotatably supporting said blower mechanism, an annular rack on said member, a pair of pinions carried by said blower mechanism and engaging said rack, at respectively opposite sides and adapted to cause the relative rotation of said blower mechanism and said supporting member, clutch mechanism, and means actuated by the rotation of said blower mechanism on said member and adapted to shift said clutch mechanism for alternately connecting said pinions with said blower mechanism, for oscillating the same. 95 100 105

3. An air circulating device comprising blower mechanism, a member rotatably supporting said blower mechanism, an annular rack, a shaft transversely arranged with respect to the axis of said rack, pinions rotatably mounted on said shaft and meshing with said rack at opposite sides thereof, clutch mechanism, and means actuated by the relative rotation of said blower mechanism and supporting member and adapted to shift said clutch mechanism for alternately connecting said pinions with said blower mechanism, for oscillating the same. 110 115 120

4. An air circulating device comprising blower mechanism, a member rotatably supporting said blower mechanism, an annular rack on said member, a shaft carried by said blower mechanism and transversely arranged to the axis of said rack, a pair of pinions rotatably mounted on said shaft and meshing with said rack at opposite sides thereof, clutch mechanisms carried by said shaft adjacent to said pinions, and means actuated by the relative rotation of said blower mechanism on said supporting member and adapted to shift said clutch mecha- 125 130 135

nisms for alternately connecting said pinions with said blower mechanism, for oscillating the same.

5. An air circulating device comprising a blower mechanism, a member rotatably supporting said blower mechanism, an annular rack on said member, a shaft carried by said blower mechanism and transversely arranged to the axis of said rack, means rotatably connecting said shaft to said blower mechanism, a pair of pinions loosely journaled on said shaft and meshing with said rack at respectively opposite sides thereof, clutch mechanisms splined on said shaft adjacent to each of said pinions, means connecting said clutch mechanisms and adapted to cause said clutch mechanisms to shift so as to connect one of said pinions with said shaft and disconnect the other pinion, and 15 coacting shoulders carried by said blower mechanism and said supporting member and adapted to be actuated by the relative rotation thereof for shifting said clutch mechanisms so as to cause the oscillation of 20 said blower mechanism.

6. An air circulating device comprising a blower mechanism, a member rotatably supporting said blower mechanism, an annular rack on said member, a shaft carried by 30 said blower mechanism and transversely arranged to the axis of said rack, means rotatably connecting said shaft to said blower mechanism, a pair of pinions loosely journaled on said shaft and meshing with said 35 rack at respectively opposite sides thereof, clutch mechanisms splined on said shaft adjacent to each of said pinions, a rod shiftably mounted at one side of said shaft, transversely disposed arms on said rod respectively engaging said clutch mechanisms, said rod and arms being arranged so as to 40 shift one of said clutch mechanisms to connect with one of the pinions when the other of said clutch mechanisms is disconnected from its respective pinion, lugs on said 45 clutch mechanisms, an arm arranged on said supporting member and adapted to engage said lugs for shifting said mechanisms, and means adapted to yieldingly hold said rod in either of its shifted positions.

7. An air circulating device comprising a blower mechanism, a member rotatably supporting said blower mechanism, an annular rack on said member, a shaft carried by said blower mechanism and transversely arranged to the axis of said rack, means rotatably connecting said shaft to said blower mechanism, a pair of pinions loosely journaled on said shaft and meshing with said 55 rack at respectively opposite sides thereof, clutch mechanisms splined on said shaft adjacent to each of said pinions, a rod shiftably mounted at one side of said shaft, transversely disposed arms on said rod respectively engaging said clutch mechanisms, said rod and arms being arranged so as to 60 shift one of said clutch mechanisms to connect with one of the pinions when the other of said clutch mechanisms is disconnected from its respective pinion, legs on said 65 clutch mechanisms, an arm arranged on said supporting member and adapted to engage said lugs for shifting said clutch mechanisms, said rod having notches formed therein, and a detent shiftably mounted adjacent to said rod and yieldingly urged into 70 engagement with said notches.

8. An air circulating device comprising a blower mechanism, a member rotatably supporting said blower mechanism, an annular rack on said member, a shaft carried by said blower mechanism and transversely arranged to the axis of said rack, means rotatably connecting said shaft to said blower mechanism, a pair of pinions loosely journaled on said shaft and meshing with said 75 rack at respectively opposite sides thereof, clutch mechanisms splined on said shaft adjacent to each of said pinions, a rod shiftably mounted at one side of said shaft, transversely disposed arms on said rod respectively engaging said clutch mechanisms, said rod and arms being arranged so as to 80 shift one of said clutch mechanisms to connect with one of the pinions when the other of said clutch mechanisms is disconnected from its respective pinion, lugs on said 85 clutch mechanisms, an arm arranged on said supporting member and adapted to engage said lugs for shifting said mechanisms, and means adapted to yieldingly hold said rod in either of its shifted positions.

9. An air circulating device comprising a blower mechanism, a member rotatably supporting said blower mechanism, an annular rack on said member, a shaft carried by said blower mechanism and transversely arranged to the axis of said rack, means rotatably connecting said shaft to said blower mechanism, a pair of pinions loosely journaled on said shaft and meshing with said 90 rack at respectively opposite sides thereof, clutch mechanisms splined on said shaft adjacent to each of said pinions, a rod shiftably mounted at one side of said shaft, transversely disposed arms on said rod respectively engaging said clutch mechanisms, said rod and arms being arranged so as to 95 shift one of said clutch mechanisms to connect with one of the pinions when the other of said clutch mechanisms is disconnected from its respective pinion, lugs on said 100 clutch mechanisms, an arm arranged on said supporting member and adapted to engage said lugs for shifting said mechanisms, and means adapted to yieldingly hold said rod in either of its shifted positions.

10. An air circulating device comprising a blower mechanism, a member rotatably supporting said blower mechanism, a transversely disposed annular flange on said sup- 105

porting member having a rack formed thereon, a shaft carried by said blower mechanism and arranged transversely to the axis of said flange, means rotatably connecting said shaft with said blower mechanism, rollers journaled on said shaft at opposite sides of said flanges and bearing thereon, pinions journaled on said shaft adjacent to said rollers, clutch mechanisms shiftably mounted on said shaft adjacent to each of said pinions, means carried by said blower mechanism and adapted to cause said clutch mechanisms to shift so as to connect one of

said pinions with said shaft and disconnect the other, a finger carried by said means, and inclined shoulders on said supporting member adapted to engage said finger for actuating said shifting means.

Signed at Chicago this 10th day of September, 1913.

LOUIS GREENBERG.
GUSTAF OLSON.
